US00D942991S

(12) **United States Design Patent** (10) **Patent No.:** **US D942,991 S**
Matsuura (45) **Date of Patent:** **** Feb. 8, 2022**

(54) **DISPLAY SCREEN OR PORTION THEREOF WITH GRAPHICAL USER INTERFACE**

(71) Applicant: **HOKURIKU Techno-Solutions Co., Ltd.**, Toyama (JP)

(72) Inventor: **Yoichi Matsuura**, Toyama (JP)

(73) Assignee: **HOKURIKU Techno-Solutions Co., Ltd.**, Toyama (JP)

(**) Term: **15 Years**

(21) Appl. No.: **29/694,201**

(22) Filed: **Jun. 7, 2019**

(51) LOC (13) Cl. **14-04**

(52) U.S. Cl.

USPC **D14/486**; D14/492; D14/491

(57) **CLAIM**

The ornamental design for a display screen or portion thereof with graphical user interface, as shown and described.

DESCRIPTION

The FIGURE is a front view of a display screen or portion thereof with graphical user interface showing my new design.

The outer perimeter illustrated by a broken line in the drawing illustrates a display screen or portion thereof and forms no part of the claimed design. The remaining broken lines in the drawing illustrate portions of the graphical user interface that form no part of the claimed design.

1 Claim, 1 Drawing Sheet
